UNITED STATES PATENT OFFICE

EUGEN PRESTINARI, OF IRVINGTON, NEW JERSEY, ASSIGNOR TO GEMEX COMPANY,
OF NEWARK, NEW JERSEY, A CORPORATION OF NEW JERSEY

DESIGN FOR A BRACELET STRAP

Application filed January 28, 1930. Serial No. 34,324. Term of patent 3½ years.

To all whom it may concern:

Be it known that I, EUGEN PRESTINARI, a citizen of the United States of America, residing at Irvington, county of Essex, State of New Jersey, have invented a new, original, and ornamental Design for Bracelet Strap, of which the following is a specification, reference being had to the accompanying drawing, forming a part thereof.

Fig. 1 is a plan view; Fig. 2 is a side elevation; and Fig. 3 is a sectional end view of a bracelet strap, showing my new design.

I claim.

The ornamental design for a bracelet strap, substantially as shown.

EUGEN PRESTINARI.
